TYPEWRITING MACHINE

Burnham C. Stickney, Hillside, N. J., assignor to
 Underwood Elliott Fisher Company, New York,
 N. Y., a corporation of Delaware

Application January 18, 1934, Serial No. 707,055
 Renewed February 19, 1936

38 Claims. (Cl. 197—22)

This invention relates mainly to the reorganization of a typewriting machine.

Heretofore, it has been the practice to manufacture a standard Underwood or other typewriting machine, by providing a single heavy framework of cast iron, and using the same as a general mount for the numerous trains and moving parts. They were usually mounted directly upon said cast-iron framework, which generally included a base, four corner-posts, and top plates or members seated upon the posts and having guide-tracks for the paper-carriage.

In the usual manufacture of such machines, there occurs the drawback that a very heavy stock of cast-iron frameworks of many varieties has to be stored in the factory, including some with tracks of ordinary length for ordinary carriages, some with tracks of greater length for longer carriages, and some with tracks of extreme length for the longest carriages.

Standard typewriting machines are manufactured in such great variety that it became necessary either to manufacture and carry constantly in stock many complete machines of every variety, or else to carry in stock merely the cast-iron frames, and some other parts, and to proceed to construct the machines, one by one, as orders came in, thus incurring delay in delivery to the customer, and of course postponing the date at which the customer could be charged for the machine.

In the general run of machines, there are differences in the sizes and styles of types, differences in the number of keys on the keyboard, differences in the characters of the keys for different languages, differences in the extent of stepping movement of the paper-carriage, involving corresponding differences in the margin-gage mechanism and in the tabulating mechanism, differences in the length of carriage-driving spring, etc.

In the Underwood machine, the platen is shifted up and down for typing capital letters, but the type-bars and keys are mounted upon the non-shifting heavy breakable general framework.

According to the present invention, there is disclosed a general reorganization in the support and assembling of the many trains, for the purpose of overcoming the above-mentioned difficulties, and gaining further advantages. In reorganizing the machine, the general cast-iron framework is discarded, with its permanently mounted type-bar and key-mechanism, ribbon-mechanism, and other mechanisms, and there is substituted a system of separable units, each

complete in itself, the units being manufactured separately as complete units, and being interchangeable.

While some of the novel machines may be completed at the main factory, still it is an aim of the invention to supply local dealers with stocks of units, enabling him to fill an order for a complete machine usually within a few hours of its receipt, so that the customer, desiring a machine having any desired type-system, any desired keyboard, any desired length of carriage, any desired pitch of letter-spacing movement of the carriage, and so on, might order in the morning, and receive the completed machine in the afternoon; whereas, heretofore, weeks might elapse between the receipt of the order by the dealer and the delivery of the machine to the customer.

The dealer, according to the present invention, could carry a moderate stock of bases. These bases, for lightness, stiffness, cheapness and safety from injury, could be struck up from sheet-steel. Great economy is attainable thereby, inasmuch as each base is universally interchangeable, that is, it can be used for filling any order for any kind of machine, and by itself forms a complete unit.

The dealer may also carry a supply of all the popular varieties of type-action units. Each type-action unit, according to the present invention, has its own frame or skeleton, and is a complete and separate article of manufacture. Any one of scores of varieties of type-action units may be inserted in the universal base, and fastened by a few screws. Thus, the assembling of the machine may commence by placing in the universal base a type-action unit having say italic types, with a pitch of say nine spaces to the inch, and a keyboard of say forty-four keys. Or the type chosen by the customer may be "elite", "pica", or other style, or types may be selected for writing a foreign language. All that the dealer needs to do, is to pick out the type-action unit from his stock, and fasten it in the base.

The type-action is complete, with type-bars and segment, and provides for shifting the same bodily up and down; this unit including the shift-key mechanism. This involves a departure from prior Underwood machines, in which the platen was shiftable up and down on the carriage by means of a key-mechanism which was mounted in the non-shifting base of the main framework. By the present invention, in providing for the types and segment to shift up and down upon

45

50

55

the type-action unit, it is made feasible to place the entire shift mechanism also upon the type-action unit, and to avoid the necessity of mounting the complex shift-key mechanism directly 5 upon the stationary universal base.

The type-action unit, with the shift keys and shifting type-bars, and the ribbon-vibrating train, may constitute the principal portion of the mechanism of the typewriter. It may be inexpensively 10 produced, inasmuch as it includes a sheet-metal skeleton, upon which all its parts are mounted, all parts of this unit being readily accessible for cheapness of manufacture, and precision being gained for the mounting and striking of the types, 15 so that the unit, although being devoid of a platen, may still be interchangeably mounted, that is, it may combine with any kind of platen and carriage, and the types may be pre-aligned and pre-tested, so that the typing will be found to be even, 20 precise and exact, and to necessitate no aligning operation after assembling.

Then the dealer may assemble upon the type-unit a ribbon winding and reversing unit, which itself is a separate article of manufacture, and 25 is adapted to work with any variety of type-action unit; so he needs to carry in stock only a moderate supply of ribbon-winding units.

The dealer then selects a carriage of the length chosen by the customer; the carriage of course 30 being a separate complete unit. He further selects a carriage-track unit of the length required for the selected carriage.

The carriage-track unit constitutes the upper portion of the completed typewriter-framework. 35 It is fastened down upon four short corner-posts that rise from the base, which is termed "universal" because carriage-track units, of any length, can be interchangeably fastened thereon, and any kind of type-action unit can be fastened 40 therein.

The dealer may put a margin-gage unit in place upon the carriage-track unit. The entire margin-gage and key-locking mechanism constitutes a sub-unit which is a separate article of 45 manufacture and is mountable upon any carriage-track unit, and together therewith may be applied to or separated from the universal base and its type-action unit.

The dealer may also fasten in place a carriage-escapement unit, having provision for feeding the carriage the required fraction of an inch at each step.

The dealer may also assemble a back-spacing unit upon the carriage-feeding unit.

55 The dealer also assembles upon the carriage-track unit a driving barrel having the right length of spring for driving the selected length of carriage.

There may be added a tabulating unit. 60 There is then placed upon the machine a separable finishing mask, with sides rising from the bottom of the machine up to the level just under the paper-carriage. The mask may extend forwardly around the keyboard and upwardly in rear 65 of the universal base, to impart an attractive appearance and add to the salability of the machine. Other details of the units and assembly thereof will hereinafter appear.

It will be perceived that the stock of manufactures carried in the main factory may be vastly reduced, and that a dealer or branch may be supplied with a moderate stock of units instead of having only a scarcity of completed machines; and that he may fill orders without waiting for the 75 factory, and that his depleted stock may be

promptly replenished, either from a nearby depot or directly from the main factory.

The entire machine is reduced in weight, while it exhibits the same impressive massiveness, and is even more attractive than prior machines. 5

The construction of the machine is very rigid, with its sheet-metal universal base and type-action skeleton re-enforcing each other, and with the top or carriage-track frame giving further re-enforcement, and completing a box-like rigid 10 structure, said top frame being of cast iron, and contributing to the massive appearance of the machine.

If the owner of a machine finds that occasion arises when he must use wider sheets, and must therefore have a longer carriage, he does not have to buy a new machine, as heretofore. He can take his machine to the dealer and have his old carriage and carriage-track removed, and a new one substituted therefor, all within a few minutes, 15 at relatively small expense. Likewise if he desires to change the style of type in his old machine, or the extent of the letter-feeding movement of the carriage, etc. All such changes are readily and cheaply made in machines that still belong to the 20 customers.

It will be further perceived that for servicing and repair of the entire mechanism of the typewriter, the present invention affords improved 25 facilities.

It will be found to require only a few moments to take off four top screws and lift the carriage-track frame off from the machine, together with the carriage thereon, without even disconnecting the carriage-driven strap. The mask being also removed, the entire mechanism in the lower portion of the machine, the types, levers, ribbon-mechanism, escapement-mechanism, shifting mechanism, etc., are exposed and rendered accessible. 35

If desired, the screws which hold the type-action unit in place may be loosened, and said unit may be lifted out of the universal base, affording still better access to all parts for servicing or repairing, or for renewals of worn parts. 40

The owner of a machine that has been in use for some time may take it to the dealer and have it overhauled, and all worn parts removed and new parts substituted, and the machine returned promptly to the owner with a new mask, a new top, and reconditioned type-actions, thereby giving the owner at once a practically new machine, all at relatively moderate expense. Knowing this, the customer would be inclined to regard the purchase of the original machine more favorably, and it would therefore be apt to command a higher price than the present vogue of standard machines, with their present drawbacks. 50

If a worn machine is taken in part payment for a new machine, any one of several courses may be adopted by its original manufacturer. It may be readily taken apart for examination, and the worn-out units may be discarded and replaced by new units; or worn parts of units may be readily replaced with new parts. The carriage-track unit may be refinished, and a new mask may be installed upon the machine, so that the reconditioned machine may then be offered for re-sale by said original manufacturer, and will be found to command a high price, especially 60 in consideration of the feasibility of future renewals of worn parts or future prompt and complete reconditioning by the original manufacturer. 65

Or a machine taken in trade may be found to be so worn out and in such dilapidated condi- 70 75

tion that the best course would be to return it to a branch factory, where it may be taken down, unit from unit, and dealt with as may seem best. Numerous parts, as, for example, the universal base, which never become worn, may be salvaged, and the remainder discarded.

It will be observed that the manufacturer can readily maintain control of every machine that is taken in trade. He may control the repair or reconditioning of the same by his local branches, or by taking down the machine entirely in the main factory. In this manner, it will be seen that spurious rebuilding and the offering of cheaply repaired machines to the public at famine prices, under the claim of being rebuilt machines, under the manufacturer's own trademark (thereby injuring the reputation and goodwill of the manufacturer), can be avoided.

It will be perceived that the various units are separable, one from another, and every one by itself forms a complete interchangeable article of manufacture and commerce. Usually, owing to separability of the units from one another, each unit may be assembled all ready for operation, by merely fastening its supporting member in place upon the machine.

The unsightly units and other interior parts of the base of the machine are encased by a mask which may be inexpensively and readily attached and removed, and may present a smooth unbroken surface at the sides, front and rear of the typewriter, and may harmonize with the overhead cast carriage-track frame, and present an attractive unitary box-like appearance.

The mask may be struck up from sheet-metal, and include high side walls and a rear wall, and a member that extends forwardly therefrom from the sides to enclose the open keyboard frame portion of the universal base. The mask is permanently secured, and yet is readily removable.

The corner-posts of the universal base and also the bosses of the carriage-track frame which are fastened thereto are covered up by the mask, which may present a smooth unbroken vertical wall from the extreme rear to the extreme front of the machine. The rear wall of the finished mask may be made separately and attached to the rear corners of the universal base, forming a neat joint with the rear ends of the main mask-portion.

At the front the upper edges of the side walls may be bent inwardly to form vertical front plates; and at the top the upper edges of these portions of the mask come close up against the carriage-track frame, so that a flush or unbroken surface is presented where the carriage-track shoulders rise above the mask.

At the rear the carriage-track shoulders project outwardly through upper cutaway-portions in the side walls of the mask, and present a harmonious appearance. The carriage-track frame may be removed without disturbing the mask.

A front vertical plate extends from side to side of the mask, just in rear of the keyboard, the same having an arc-shaped upper edge, this front mask being flush with the side plates that are turned inwardly from the side members of the mask.

The front extended frame of the mask has inwardly turned beads or flanges which may fit over the underlying forwardly-extending flange-ports of the universal base.

Other features and advantages will herein-
75 after appear.

In the accompanying drawings,

Figure 1 is a sectional side elevation of an Underwood standard typewriting machine, reorganized with the present improvements.

Figure 2 is a sectional plan of the same, omitting the type-bars.

Figure 3 is a sectional side elevation of the ribbon-winding unit. The spool-cup and other members shown are duplicated at the opposite side of the machine.

Figure 4 is a sectional side elevation of the type-action unit, showing type-bars, segment, and type-operating levers in their normal upper positions, for typing lower-case letters.

Figure 5 is a sectional side elevation of the carriage-escapement unit.

Figure 6 is a sectional side elevation of the universal base. Figures 4 and 6 may be read together; as the Figure 4 unit may be dropped down into the Figure 6 unit.

Figure 7 is a sectional plan, showing the ribbon-vibrating mechanism mounted upon the type-action unit, and controlled by a linkage that extends to one side of the carriage-track unit.

Figure 8 is a sectional front elevation of the key-levers, sub-levers, type-bars, and shifting mechanism, including the type-bar segment.

Figure 9 is a perspective view of a carriage-track unit.

Figure 10 is a perspective elevation of the skeleton or frame of the type-action unit.

Figure 11 is a perspective view of the universal base.

Figure 12 is a perspective view of a cross-bar forming a part of the framework of the ribbon-winding unit.

Figure 13 is a side elevation of the Underwood machine reorganized according to the present invention, the ribbon-spoils and some other parts being omitted.

Figure 14 is a perspective view of a carriage-track unit, such as seen at Figure 9, having elongated tracks for guiding the long carriage.

Figure 15 is a sectional side elevation of a carriage-track unit and a carriage thereon.

Figure 16 is a sectional side elevation of the carriage-tabulating unit, and illustrating the separability of the keys from the key-levers of this unit, for the purpose of packing and shipment.

Figure 17 is a perspective view of the right-hand end of the carriage-track frame, showing bell-striking and line-locking mechanism mounted thereon.

Figure 18 is a sectional side elevation of the back-spacing unit which may be mounted upon the carriage-escapement unit, the latter being mounted upon a pedestal rising from the rear portion of the universal base.

Figure 19 is a perspective of the universal mask.

The keyboard has rows of alphabet and numeral type-keys 20, mounted upon stems 21 of levers 22; the latter being pivoted at their rear ends at 23 in rear of cumbent type-bars 24, the row of pivots being about on the level of the upper rows of keys 20. It will be noted that the levers 22 have rear arms 25 pendent from these pivots. At their lower portions, the arms are connected by forwardly-extending links 26 to short arms 27 of upstanding sub-levers 28 of the type-driving train. Said sub-levers 28 rise under the hubs 29 of the type-bars, about in vertical line with the type-bar pivots 30, and are connected by short rearwardly and upwardly directed links 31 to the type-bars at 32.

It will be further noted that the key-levers extend forwardly at 33 from their pendent portions 25, and then upwardly at 34 to form elbows with the forwardly-extending key-bearing portions 22. The links 26 and sub-levers 28, as well as brackets 35, to which said sub-levers are pivoted at 36, may be sunken within the transverse trough or space which is bounded by the members 25, 33, 34, thereby complying with the requirement of compactness.

When a key 20 is touched, the lever 22, 33, 34, 25 is depressed about the pivot 23, and the link 26 is pulled rearwardly, thereby vibrating the sub-lever 27, 28, and by means of the short pull 15 link 31 swinging the type to print against the platen 37.

All the above-described parts (except the platen), are mounted upon a skeleton or unit-frame which is seen in perspective at Figure 10. 20 One of the main portions of said unit-frame is a transverse vertical plate 38, to the rear face of which is detachably secured a key-lever fulcrum-rack 39 by means of screws 40. Said rack has parallel vertical guide-slots 41 for the key-lever 25 hubs, and a fulcrum-rod 23, upon which the key-levers are detachably mounted in a known manner. The key-levers are returned to normal positions by helical push-springs 43, whose tension is adjustable by screws 44, threaded into a bar 30 45, which is mounted at its ends upon ears 46 bent from the ends of arms 47 which extend rearwardly from the opposite sides 51 of the unit-frame.

At their front ends, the key-levers are guided 35 in a transverse vertically-slotted comb 48, secured by screws 49 to ears 50, bent up from the front of the side members 52 of the unit-frame.

From the ends of said plate 38 are bent forwardly vertical opposite side plates 51 which rise 40 from a pair of sills in the form of horizontal angle-bars 52 that extend forwardly and rearwardly from the side plates or posts 51, and include outturned horizontal front and rear flanges 53, 54. By means of these sills the unit-frame 45 is detachably secured by screw-holes 52^a upon the floor of the main frame which will presently be described.

From the foregoing, it will be seen that the 50 unit, at Figure 4, is intended to embody all the type-keys, as well as the type-bars and the connections from the keys to the type-bars.

In order to simplify the Underwood carriage and reduce its weight, and to gain further advantages, it is also provided that the types on this 55 key-action unit shall be shiftable up and down, for printing upper and lower case letters. To this end, the type-bars 24 and the segment 55, whereon they are pivoted, are mounted for bodily up-and-down shifting movement at the operation 60 of a shift-key.

It will be seen that said segment 55 is fastened by screws 56 to an upstanding shift-frame that is pivoted at its upper end at 57 to the forward end of idle guide-arms 58, and pivoted at its lower end at 59 upon the forward ends of shift-arms 60. Said arms 60 extend forwardly from a transverse rock-shaft 61.

The shift-frame is of open design, as seen in 70 the front view in Figure 8, and includes a top transverse bar 62, to which the upper portion of the type-bar segment is fastened at both ends by the screws 56. The sheet-metal shift-frame also includes opposite side bars 63, bent downwardly and outwardly from the ends of the trans-

verse bar 62. At their lower ends these side bars are tied by a segmental transverse bar 64.

To the front face of bar 64 are fastened individual brackets 35 for the vertical sub-levers 27, 28, which are secured thereto by nuts 66, threaded upon stems which pass through the wall of transverse bar 64.

The open segmental frame 62, 63, 64 swings up and down upon the guide plates or arms 58, 60, together with the type-bar segment and type-bars, as well as the type-bar-operated levers 27, 28, and their individual brackets 35. During the shifting operation, the forward ends of the links 26 vibrate up and down idly about their rear pivots at 67, without operating the type-bars 24. 15

The system of type-bars is narrower than the system of key-levers, and this difference is compensated by fanning out or spreading the lower portions of sub-levers 27, 28, while their upper portions remain connected to the operating links 20 31, and work substantially in the respective radial planes of their type-bars. These sub-levers are guided in their own radial planes by means of the brackets 35, which are provided with guiding surfaces, as seen at Figure 8, between which 25 the sub-levers work. At their lower ends, the sub-levers work in approximately horizontal directions, and approximately within the vertical planes of movement of their respective key-levers. Thus all side strain and liability of binding and 30 retarded action are avoided.

Opposite ears 68 are provided upon the side bars 63 of the shift-frame, for receiving the upper pivots 57, while the bottom ears 69 receive the lower pivots 59.

The shifting mass is normally held elevated by a spring 70 upon the rock-shaft 61. Depression of shift-key 71, also mounted upon this unit, operates levers 72, pivoted at 73; the rear end of the lever rolling against the under edge of an 40 arm 74 that extends back from rock-shaft 61 of the shifting mechanism. Thus depression of the shift-key causes the type-bars to drop, and the spring 70 restores them when the key is released. 45

The up-and-down movements of the shift-frame may be gaged by upper and lower adjustable screws 74^a, 74^b, which are threaded into opposite ears or portions 74^c of a strip 74^d, which is raised from the sill 54 at each of the opposite sides of the unit, and bent to form parallel portions to receive said screws. The latter operate with the studs 59 to arrest the shifting mass.

In order to operate the letter-feeding mechanism of the carriage, the key-levers are provided with bendable arms 75, of different lengths, to press down uniformly a transverse horizontal universal bar 76, which is carried upon this unit by means of arms 77 extending back from a 60 transverse rock-shaft 78. An arm 79 upon said rock-shaft 78 is connected by a link 80 with an arm 81 pendent from a pivot-stud 82; the latter carrying a striker 83 for operating the carriage-feeding mechanism, and also having a forwardly-extending arm 84 for operating a ribbon-vibrator 65 85 up and down in front of the platen at the key-strokes.

In the general organization, this interchangeable type-action unit serves as an important element, partly because it includes all the case-shift and type-operating devices. The case-shift set usually includes one or more keys at each side of the keyboard, with appropriate connections for operating, and also releasing connections, not 75

shown; and it is a feature of the invention that it is rendered practicable to mount the key-shift train upon this unit, by also providing, upon the unit, mechanism for shifting the type-bar system of the unit up and down.

5 Shifting the type-bars up and down is facilitated by the up-and-down vibrating type-bar links 26, which are made to operate the pull-arms 27 on the sub-levers 28; this being rendered practicable by pivoting the links 26 in rear to the non-shifting pendent key-lever arms 25, and having said shifting sub-levers, with their brackets, sunken in a well or trough which is bounded by said arms 25 and the members 33 and 34 of 10 the key-levers; while the lower portion of the shift-frame, which carries said sub-levers, is also sunken in said trough. In this way compactness and lightness are secured.

The above-described unit is seen by itself at 20 Figure 4, and is a separate article of manufacture. It may be readily positioned upon the floor of the typewriter after the overlying carriage-rail unit has been taken out of the way; and it may readily be secured through screw- 25 holes 52^a to the floor of the main frame, which is seen at Figure 11, provided with threaded holes 52^b for this purpose.

The assembling of the many parts to the type-action frame, seen at Figure 10, is a cheapened 30 and simplified operation, owing to the accessibility of all portions of the unit, as well as to its lightness and ease of manipulation; whereby substantial reduction may be figured in the cost of manufacture of the typewriter.

35 The skeleton or unit-frame 38, 52, 53, 54 may be inexpensively stamped out from sheet-metal and bent into form, and affords lightness and strength. The cross-bar 48 serves as a tie to connect the front ends of the sills 52 and complete the box-like stiff frame.

The unit may be thereafter readily removed from the machine, rendering all the parts accessible for inspection, adjustment, cleaning, repairing, and replacement of worn parts.

45 The tension of the keys may be very readily and delicately regulated by adjusting the screws 44 which are exposed and accessible while the unit is outside of the machine; and at this time the effect of the tension-regulation may be readily ascertained, so that perfect adjustment may quickly be effected.

This unit may be securely and cheaply packed, owing to its lightness and compactness, and large quantities of units may be dispatched in 55 one shipment with reduced cost for transportation, and with reduced liability to injury; presenting an advantage over the shipment of an ordinary typewriter, which combines a large and heavy main frame permanently with a complicated delicate mechanism.

This unit also overcomes the drawback that much factory room has to be used for long periods in storing large typewriter-frames, while waiting to have the working parts built into 60 them.

The bending or adjustment of the universal-bar-operating fingers 75 is very easily effected, these parts being readily accessible when the unit is inverted or set up on edge; and the testing of the universal-bar operation may be made.

Without putting the unit into the typewriter, it is made sure that the unit and the paper-carriage will co-operate, and it is also made sure that the types will type accurately upon the 65 platen in any typewriter-frame into which the

unit may be secured. It will be understood that the unit must fit with accuracy upon the floor of the main frame, and that said floor must be accurately finished with respect to the position of the platen, and with respect to the carriage-feeding dogs, which will presently be described; so that, when a unit is placed interchangeably in any typewriter-frame, immediate and accurate operation of the machine can be depended upon.

10 The keys and connections may be installed and the types operated and tested by the aid of a dummy platen, and the manufacture of the unit may be entirely completed, so that it may be boxed and shipped without being accompanied by other portions of the machine.

15 It will be seen that a dealer may be supplied with an assortment of these separate type-action units, so that, by selecting a unit from said assortment, he can supply to a customer any 20 desired machine, having either pica or elite, or gothic, or any other style of type, or types and keys for Hebrew, or Arabic, Greek, or other language.

25 If, for example, a dealer has a call for a Greek typewriter, he needs only to take from stock a unit having the Greek types and keys, and put it in place in the main frame of the machine, to complete the typewriter, which can be delivered to the customer within a few hours of purchase; or, in case the dealer has no main frame available, he can remove the type-action unit from an English typewriter, and replace it by a unit 30 having the Greek types and keys; and thus secure prompt delivery.

35 When a customer sends back a machine for overhauling, this type-action unit may be readily detached and withdrawn, first moving the carriage-track frame out of the way; and the unit may be cleaned by a bath, using kerosene, 40 naptha, alcohol, or the like, and then its joints may be oiled; and then, without refinishing, it may be restored to its place in the typewriter.

45 Or, if a used machine is taken in trade, the type-action unit may be removed and worn parts readily replaced by new ones, and the renovated restored typewriter may be exposed for sale by the original manufacturer or his agent, with a new shell or mask.

50 In some cases, an entire new unit may be substituted for an old unit, and the latter may be returned to the main factory for such disposal as may be proper, and for use partially or wholly in either new machines or remanufactured machines.

55 Any individual type-bar may be removed, after withdrawing a curved keeper 86, which fits upon the circular hubs 87 of the type-bars, to retain them upon the fulcrum-wire 30. The type-bar is in the form of a hook, and may be 60 lifted off from the hub-wire, and may then be detached from the buckle-link 31, and withdrawn from the machine and replaced by a new type-bar. The keeper is detachably secured by 65 screws 88.

70 The type-bar is formed with a member in the form of a guide-plate 29, and the body of the bar extends at about right angles to said plate, which guides the bar in the radial slot of the segment 55. The guide-plate member merges into the hook-like hub member 87 which hooks upon the fulcrum wire, where it is retained by the keeper 86, the contour of the hub member being segmental, or concentric with the fulcrum pin for about 90 degrees or more. The hook is formed by an open 75

slot which permits attachment and removal of the type-bar when the keeper is removed. This slot is bordered by a short arm member which projects from said plate-like member and at its 5 end has the pivot bearing 32 whereby the link 31 is pivoted thereto. The link is preferably cast off before removal of the type-bar.

If desired, the segment, which forms a sub-unit, may be detached independently of the key-levers and sub-levers; the links 31 being first detached from the type-bars. The segment 55 is generally of Underwood formation, having stop-ring and dust-guard formations, and is detachably held upon the shift-frame 63 by means of 15 screws 56, and may be removed with its type-bars independently of the frame and of the type-rest 89, which latter is carried by rods 90 that are anchored in the main shift-frame 63.

If it is merely desired to remove an old type-head 91 from any type-bar 24, the unit may be removed from the typewriter, thereby exposing all the type-heads and type-bars to the operations of the machinist, and the old type may easily be taken off from the bar, and a new one soldered 25 in place thereof.

The segment may carry the usual central type-guide 92, upon which is guided the aforesaid ribbon-vibrator 85. Said vibrator may be operated by an arm 93. This arm has an elbow 30 shape, and is pivoted at 94 to ears 95, bent forwardly from the vertical main plate 38 of the unit. The keys cause the arm 84 to rock the ribbon vibrator arm 93 up and down, so as to bring the ribbon up to the printing-point and 35 then drop it. For this purpose, the arm 84 may carry opposite pins 96, which may engage alternate slots 97, 98. Either slot may be brought into use to connect the arms 84 and 93, by shifting, crosswise of the machine, a yoke 99, in which are 40 formed said slots 97, 98.

This yoke, movably attached to the arm 93, may be shifted by means of a transverse link 100, Figure 7, thereby bringing either slot 97 or 98 into use. Each slot is made reversely curved, so 45 as to start the ribbon-vibrator up slowly, and accelerate its upward motion, and finally to reduce the upward motion to effect a gradual stop, thereby avoiding initial wrinkling of the ribbon, and also avoiding final overthrow of the ribbon.

The right-hand end of the link 100 may be connected to an arm 101 of a detachably mounted lever 102, such as seen in Helmond Patent 1,834,522, for bringing into use different stripes of a bichrome ribbon, and for also silencing the 55 ribbon for stencil-typing. The right end of said link is detachably pivoted at 103, and it may vibrate up and down idly at the ribbon-vibrating operation.

The detachable link 100 and the lever 102 may 60 be packed separately, and then put in the same package with the type-action unit, to be shipped therewith; and it will be found convenient to attach the part 100 to the yoke 99 on the ribbon-vibrator operating lever 93 and pivotally connect the lever 102 to a lug 102* provided therefor in the carriage-rail frame, so as to complete the type-operating mechanism.

A space bar or key 104, at the front of the keyboard, is carried upon parallel arms 105, fixed 70 upon a transverse rock-shaft 106, provided with a key-returning spring 107. Each arm is provided with a riser 108, from which projects the pin 109, these pins overhanging the opposite arms 75 71 of the universal-bar structure, to depress the latter for the usual purpose.

A detachable ribbon-unit includes the usual Underwood transverse driving shaft 110, with its pinions 111 meshing with pinions 112 on the lower ends of vertical spool-shafts 113, which at their upper ends drive spools 114, the latter being detachable from the shafts. Upon the winding shaft 110 is the usual driving ratchet-wheel 115. The usual automatic reversing mechanism includes a swing-arm 116, which has a fork 117 through which the ribbon is threaded.

At each end portion the ribbon has usually an obstruction, which encounters the fork, whereby shaft 118 is rocked to reverse the travel of the ribbon, in a known manner. These vertical shafts in the Underwood machine are usually mounted in a vertical bracket 119; but in the present instance said bracket is modified by being provided with a boss 120, which is secured by screws 121 to a sheet-metal bracket (Figure 12) in the form of a transverse plate 122 that extends under the type-bars 24 from side to side of the machine, and has end risers 123 to which the bosses 120 are secured. The body of the bracket 122 is detachably secured by screws 124 upon opposite risers 125 which extend up from the sills 25 52, Figure 10.

It will be observed that this ribbon-winding unit may be manufactured and shipped separately from the type-action unit, inasmuch as the ribbon-mechanism will serve for any kinds of types, so that it is rendered unnecessary to add to the cost of the type-action unit by permanently building the ribbon-winding mechanism thereon.

The ribbon-winding unit may be set in place by passing it rearwardly with the cross-bar 122 under the type-bars 24, and then it may be set upon the risers 125 and attached by the screws 124, whereupon the combined type-action and ribbon-unit may be secured in place in the machine.

When the type-action unit is thereafter removed, the ribbon-unit comes out with it, and may then be detached from it, for servicing or other disposition as may be required, without disturbing the mechanism of the type-action 45 unit.

It will be remembered that the carriage-rail unit must be taken off from the machine whenever the type-action unit, with or without the ribbon-unit, is to be removed or replaced; and 50 it will be seen also that the ribbon-winding unit can be put in place upon the type-action unit after the latter has been fastened in the universal base of the machine. In other words, after removing the carriage-track unit, the ribbon-unit 55 may be withdrawn for any purpose, and then replaced or a new one substituted without disturbing the type-action unit.

To render such use of the ribbon-unit feasible, it is provided that the ribbon-winding ratchet-wheel 115 shall be operated from the type-action unit by means of universal bar 126 on the latter; and the operating train from the universal bar to the ratchet-wheel is made divisible or separable, one part of the train remaining connected 65 to the universal bar, and the other part of the train being mounted upon the main bracket 122 of the ribbon-winding unit.

Said main bracket is provided with an ear 128 in which is pivoted at 127 a lever, one arm 70 128 of which is operated by a thrust-rod 129, and the other arm 130 of which is pivoted at 131 to a winding pawl 132, which drives the ratchet-wheel 115 at the type-strokes to rotate the shaft 118 and wind the ribbon; said pawl having a re-

turning spring 133, and the lever having a returning spring 134.

Said rod 129 is pivoted at its lower end at 135 to an arm 136 upon the rock-shaft 78 of the universal-bar structure, and is guided by a pin 137 and extends upwardly and forwardly. At its free end the rod thrusts up the ribbon-feeding arm 128, without, however, being attached to the latter, this being the point of separation between the winding mechanism upon the ribbon-mechanism and the universal-bar mechanism upon the type-action unit.

There is also provided a spring-detent 138 for the ratchet-wheel 115.

15 The above-detailed units, as well as the carriage and its tracks and the remainder of the typewriting machine, are all supported upon a base 139, seen at Figures 6 and 11, which is interchangeable and universal, that is, it is the same for all machines, whether they have long or short carriages, or one kind or another of type-systems, etc.

This universal base, which is open at its top, may be struck up from one piece of sheet-metal. 25 It has a floor 140, from the sides of which the bent up opposite side walls 141, 142; the floor having large transverse cutaways 143, 144, 145 for lightness. From the rear of the floor may be bent up a rear wall 146, and from the front may 30 be bent up a front wall 147 to confine the keyboard.

These side, front and rear walls form integral flanges, which co-operate with the floor to make a boxwork having great stiffness and lightness, 35 and possessing the further advantage over the usual cast-iron frame in that the soft sheet-steel is not liable to breakage. The stiffness may be increased by riveting the rear wall at 148 to integral flanges 149 turned inwardly from the 40 rear ends of the side walls.

Rubber feet 150 may be attached directly to the bottom of this universal base by means of screws 151, which may be headed in the known manner and passed up through the rubber feet 45 150 and the metal caps 152 thereof, and threaded into ears 153, which extend out from opposite sides of the floor. By this simple means there is secured a cushioned support of ample breadth for the machine.

50 This universal base is further stiffened by the skeleton frame 38, 48, 52 of the type-bar unit, which skeleton frame is seen at Figure 10 in perspective, and at Figures 1 and 2 as fastened down to the universal base. Since each frame 55 stiffens the other, each may be of lightened construction, and by this and other means the weight of the entire machine may be kept within bounds, and may even be lowered as compared with machines having the usual cast frame construction, inasmuch as this invention provides 60 for substantial reduction in use of heavy iron castings.

It will be seen that the type-action unit at Figure 4 may be dropped into the universal base 65 at Figure 6 to the position seen at Figure 1, and there secured by screws 52^c passing through holes 52^a, giving an effect of a double-wall two-part unit, which, in some cases, may be shipped in this condition from the main factory; although 70 in most cases there may be shipped separate units. In the type-action unit at Figure 10 are seen holes 52^a in the base-flange 54. The screws 52^c at Figures 1 and 2 are inserted through these holes 52^a, and fasten the Figure 10 unit to the 75 base; said screws 52^c being threaded into the

four holes 52^b provided in the base, as seen in Figure 11.

It is necessary for the dealer or branch office to keep in stock only enough universal bases to supply his customers for immediate use. An 5 assortment needs to be kept only of the type-actions and of the carriage-units, and of some other units, for the same universal base will serve for any type-action or any carriage or other unit. The cost of casting, finishing and storing an immense quantity of complete general typewriter-frames with their carriage-tracks, is avoided, and the expense of keeping such frames in storage, waiting for orders, is also avoided.

10 The principal portion of the mechanism which is seen at Figure 4 is thus mounted and confined within an inexpensive double shell of great stiffness and durability, and is readily made accessible for inspection, cleaning, repairing, replacement and remanufacture, and at low cost.

15 It has been explained that the universal bar 76 forms part of a carriage-feeding train, which includes the vibrating arm 83. This arm has a projection which strikes the usual adjustable stop 154 upon a dog-rocker 155, which includes the usual detent and feeding dogs 156 and 157, that co-operate with the usual escapement-wheel 158; the latter having a pinion 159 meshing with a releasable rack 160 upon the platen-carriage 161.

20 The dog-rocker is mounted upon the usual trunnions 162, and has a pendent stop-arm 163 to co-operate with adjustable forward and backward stops 164, 165.

25 An open frame 166 serves as a mount for the dog-rocker and the escapement-wheel, and is of about the same construction as in the Underwood typewriting machine; but in the present invention it is fastened by screws 167 upon the front of a pedestal rising from the floor 140 of the universal base, Figure 11, the pedestal having two 30 uprights 168 joined at the top by a cross-piece 169, to which the open escapement-frame is held by the screws 167. The uprights 168 may have flanges 170 riveted at 171 to the rear wall 146 of the universal base. Said mount 168, 169 may 45 also be fastened to the floor at 172.

35 As will be seen at Figure 5, the escapement-devices and their frame form an independently manufactured interchangeable unit, of which an assortment may be kept in stock by the dealer; 50 the pitch of the teeth of the escapement-wheel 158 varying in different units in the assortment, so that the dealer may select a unit having teeth of fine pitch for use with a Figure 4 unit having an elite type, or with a coarser pitch for a Figure 4 55 unit having pica type, and so on.

This unit may be attached to the support 169 either before or after the latter is assembled in the universal base. This unit controls the carriage, but is separately connected thereto, so that 60 either the unit, or the carriage, or the carriage-track unit may be removed bodily from the machine independently of the other.

This unit at Figure 5 also carries a carriage-releasing arm 173, for operation by the tabulating unit, which will presently be described; said arm having a lift roll 174 for the feed-rack 160, and a projecting part 173^a for contact with the tabulating train.

70 Since the alphabet and numerals require no more than thirty-six keys, it will be seen that the keyboard at Figures 1 and 2 is illustrated with a surplus of keys. This type-action unit may be always made of maximum size and capable of serving for the maximum number of keys that 75

may be required. Thus the dealer may conveniently keep a stock of type-action units, with a full outfit of keys and type-bars, and may remove from the selected unit its excess of keys and type-
5 actions, if necessary.

The stock of type-action units may vary also as to size of types, and as to variations in the designations on the keys for different languages, or for other uses.

10 The carrying of an assortment of type-action units would obviously be less expensive than to carry an assortment of complete machines, for different kinds of carriage-units may be required for different customers all wanting one kind of
15 type-action unit.

The dealer or branch manager may carry a moderate supply of universal bases and masks therefor, to take care of his trade for a given term, and may carry an ample assortment of carriage-track units, and an ample assortment of type-action units, and of escapement-units, and also as many ribbon-winding units as universal bases, and also a suitable assortment of tabulating units, etc., and thus find himself enabled to supply 20 each customer's needs promptly, whatever they may be, and may at the same time forward to the factory an order for whatever units are required to replenish his supply.

After the Figure 4 type-action unit has been fastened in place in the universal base at Figure 6, and the ribbon-winding unit at Figure 3 has been fastened upon the Figure 4 unit, and the carriage-feeding unit at Figure 5 has been fastened in place upon the back of the universal base
35 (the aforesaid parts then being in the positions shown at Figure 1), the top portion of the machine may be assembled thereover.

The top unit includes the carriage 161, a front carriage-track 175, Figures 9 and 15, and a rear carriage-track 176; said tracks forming rigid portions of a rectangular frame, which is detachably fastened down upon the universal base by means of corner-screws 177.

The stationary member of the carriage and track unit consists mainly of this cast-iron rectangular open frame, which includes a front bar 178 and a rear bar 179; these bars being joined at their ends by side bars 180, 181.

The front of the frame has spreading horns 182, upon which the front carriage-track 175 is detachably mounted at its ends. To the rear carriage-track 176 are fixed the usual cleats 183 which are fitted in grooved bosses 184 formed upon the ends of the rear bar 179.

55 The carriage-track frame has large bottom corner bosses or rests 185, 186, 187, 188, whereby it is seated upon the top of universal base corner-posts or risers 189, 190, the same being moderately high for minimizing liability to injury. The 60 joints are concealed by the mask. The tops of the posts are bent inwardly to form ledges 191, which combine to make a table or seat down upon which the carriage-track frame is fastened by said screws 177; and the frame may be provided
65 with corner-dowels 192, Figure 1, to fit in holes 193 in the bent-in ledges 191, and assure accurate relationship or interchangeability between the type-bars and the platen 37, which is mounted upon the carriage, so as to secure evenness
70 and accuracy of the type-impressions upon the platen 37 of the carriage.

The carriage-track frame co-operates with the reinforced shell-like universal base to make a structure of extreme stiffness, especially since the
75 universal base is reinforced by the type-action

skeleton 38, 48, 52, Figure 10. Thus the general typewriter framework is constructed of the three frames seen in Figures 9, 10, and 11. It is inexpensive and sturdy, besides possessing the numerous other advantages herein referred to; and that the advantage of a sheet-metal framework is gained, of comparative freedom from fracture, this frame being therefore superior to the cast-iron frame of the usual typewriters, since the two principal sheet-metal members of the framework are yieldable or springy and, being in the bottom position, where they take most of the shocks, they are able to withstand the shocks without injury, while the cast-iron frame (Figure 9), by being mounted upon the somewhat yieldable support afforded by said under frames, is less exposed to breakage, than is the usual cast-iron framework.

10 The cast-iron framing imparts an appearance of solidity to the machine, being largely exposed to view above the top of the mask which is presently to be described, Figure 13. Thus the machine, although cheaply made, is given an attractive, solid and substantial appearance, to conduct to salability.

15 The casting of the carriage-track element permits formations thereon which it would be expensive or difficult to make in a sheet-metal frame; while the breadth of the cast-iron frame is sufficient, although it may be substantially less than the cast-iron general framework of the usual machine.

20 The one-piece open-top frame has the further advantage that the seats for the rear track cleats 183 and the seats for the front track 175 may 30 all be milled at one operation, thus insuring accuracy in the position and relationship of the tracks to each other. Underwood machines have no integral front and rear cross-bars 178, 179.

25 This rectangular cast frame is compact and 40 may be stored in reduced quantities, each frame requiring only a small fraction of the room that is now demanded for storage of a cast-iron general framework. Moreover, if a track-frame should be broken, it can be cheaply replaced, and 45 not involve the loss of a whole general framework.

30 The side bars 180, 181 are about level with the top inturned edges of the side walls of the mask 194, Figure 13, and are masked thereby. The 50 front bar 178 is curved under the type-bars, Figure 1, at its middle portion, to afford access to the types for observation and cleaning. There is sufficient clearance under the types to permit the downward case-shift motion of the latter, this 55 clearance being observable at Figure 1.

35 The carriage has the usual front rolls 195 to run upon the track 175, and the rear collars 196 to slide upon the rear track 176. The platen- 60 axle 197 is mounted directly upon the carriage 161, the usual platen-shift frame being unnecessary.

40 The carriage and track unit may include the usual margin gages 198 and 198^a and the usual margin-gage rods 199, 200 and rack 201.

45 The pitch of the margin-gage rack-teeth must correspond with the pitch of the carriage-escape- 65 ment teeth 158 and rack 160, which are governed by the sizes of the types, and also the tabulator rack presently to be described.

50 In most machines, the carriage feeds ten spaces to the inch, so that by stocking up with a supply of 10-pitch carriage-track units, the dealer can supply most of his customers; and he needs carry only a moderate assortment of car- 75

riage and track units fitted with margin and spacing racks of more or less than ten-pitch. The dealer may carry a stock of carriage-track units having no margin gages or margin-gage 5 racks or letter-feeding racks; and he may also have an assortment of margin gages and letter-feeding racks of different pitches, and apply them to the carriage and track units from time to time as required to fill the orders of different 10 customers for various kinds of types.

The carriage and track unit may also include an Underwood carriage-driving spring-barrel 202, which may have a tension-adjusting knob 203, and may be mounted upon a bracket 204; 15 the operation of the mechanism being disclosed in the Helmond Patent 1,442,880, of January 23, 1923.

The bracket 204 may be attached by screws 205 to the rear bar 179 of the carriage-track 20 frame; being fastened against the front face of the rear bar 179; and a spring strap 206 may detachably connect the spring-barrel to the usual stud 207 on the carriage. This spring-barrel unit may be supplied separately from the carriage-track frame, to be attached thereto by the dealer, who may carry an assortment of spring-barrels, some with extra-length springs for use with wide carriages.

In order to accommodate work-sheets of great 30 width, long carriages may be employed, to run upon long tracks 208, 209 mounted upon a lengthened unit seen at Figure 14. This unit, although lengthened, is formed to fit upon the ledges 191 of the standard or universal base already described; 35 so that the carrying in stock of the usual widened general framework for wide-carriage machines is unnecessary. Upon the universal base may be fastened a carriage-track frame of any length; and the needs of customers may be met by simply 40 carrying in stock a moderate assortment including a few lengthened carriage-track frames, Figure 14, with their long carriages, with an appropriate small assortment of extra-length margin-gage mechanism and carriage-feeding and tabulating racks.

It will be understood that extra-long frames, Figure 14, may be made both shorter and longer than illustrated. The horns for carrying the front track may rise from spreading horizontal 50 trunk-portions 210, terminating in upstanding tips 211 to which the track is fitted.

The rear bar 179 may have extension trunks 212 carrying at their ends the carriage-bosses 188 for the carriage-track cleats 183. For supporting the middle portion of the lengthened rear carriage-track 209, there may be provided midway spaced cleats 213, similar to the cleats 183, and fastened upon bosses 214, similar to 188, and integral with the carriage-track-frame casting. 60 The barrel 202 on this unit at Figure 14 may contain an extra-length spring.

It is a simple matter to keep an assortment of margin-gage racks and other racks for different lengths of carriages, and for each length to include a small number of racks of unusual pitch, while the bulk of the stock racks may be of standard ten pitch.

A further advantage is gained in substantially placing the usual margin-gage mechanism upon 70 the carriage-track frame to form a portion of that unit for boxing and shipment therewith, or for keeping in stock therewith, the same to be brought into its proper place in the finished machine by simply attaching the carriage-track unit 75 to the universal base. The local dealer may carry

margin-stops, rods and racks of different lengths, and with teeth of different pitch, so that, although keeping on hand a very small assortment of carriage-track rails of any given length, he may, by having a larger assortment of margin-gage, carriage-feeding and tabulating racks, be able to equip a carriage-track frame, of the required length, with means for feeding it the required extent, without carrying racks upon the stock of carriage-track units.

The rack 200 is mounted between the horns 182 in the usual way, for limiting the return movement of the carriage 161. The usual front margin-gage rod 199 carries the rack 201, along which runs the margin-gage 198 for ringing the bell 15 and locking the line.

According to the usual Underwood method, a tongue 215 on the carriage strikes a cam 216 on one of the margin-gages, thereby depressing the rack 201 and swinging forwardly a pendent arm 217, which performs the same function as in the Underwood construction; but in the present instance the bell and line-locking train extends rearwardly and compactly inside of the carriage-track frame, along the inner side of 25 the bar 181.

This arm 217 extends rearwardly and has pivoted thereto a trip-arm 220 having a pin 218. When the arm 217 is depressed, the pin 218 strikes the bell-hammer 221 to first raise it, and then 30 allow it to fall upon the bell 222, which may be mounted in the rear right-hand corner of the carriage-track frame.

As the carriage proceeds, the arm 217 is cammed down still farther, and encounters a lug 35 223 placed upon a rod 224, which rod operates a lever 225 pivoted upon a boss 225^a of the carriage-track frame, lifting up the interponent 226 therefrom into the path of a stop 227, which is formed upon the top of the striker 83, Figure 1, and 40 swings rearwardly to strike the escapement-dog rocker to feed the carriage. When the interponent 226 rises into place, the striker 83 cannot operate, and hence no numeral-key or space-key can be fully depressed, and hence the line is 45 locked.

When it is desired to write a few additional letters at the end of the line, a key 228, at the rear of the keyboard, is depressed to swing its bell-crank 229, which is pivoted at 230 upon a 50 hanger 231 pendent from the carriage-track frame. To this bell-crank is connected the forward end of the rod 224, whereby the lug 223 may be pulled forwardly out of the path of ear 232.

When the carriage with the tongue 215 depresses the cam 216, the ear 232 presses down the lug 223 and with it the rod 224 and the lever-arm 225, thereby lifting the interponent 226 into the path of the stop 227 on the feed-dog striking arm 83. Now when the key 228 is depressed, the 60 rod 224 is pulled forwardly and the lug 223 is therefore pulled out of the path of the ear 232, so that said arm 217 can no longer control the rod 224.

Hence a spring 233 may lift the lever-arm 225 65 independently of the carriage-operated arm 217, and the interponent 226 may thereby be dropped out of the path of the striker 227 on the escapement-dog striker 83, so as not to interfere with the action of the type-striking keys.

The key 228, the lever 225, the bell-striker, and some other portions of the margin-gage and key-locking train may be supplied with every carriage-track unit; and these parts may be the same for carriage-track units of all sizes. The 75

arm 217 may be attached to the margin-gage rack by screws 234, and said arm may be supplied with every carriage-track unit, and the local or branch dealer may attach it to the rack 201.

5 The margin-release key, which is at the right-hand side of the keyboard, is seen at 228 (Figure 13), substantially in line with the rear bank of type-keys, but at a greater elevation corresponding with the position of the back-spacing key, 10 seen at Figure 1, which is at the left-hand side of the keyboard.

Before removing the carriage-track frame from the universal base, the carriage should be run along to a central position, and then the right 15 and left margin-gages should be run along toward each other until they meet the usual carriage-lugs, so that the carriage cannot move to right or left when the carriage-track frame is lifted off from the universal base, and the carriage-rack 160 therefore lifted off from its pinion 159. Thus the carriage will be restrained from running along its tracks in either direction, and liability of injury will be avoided.

It will be observed that the carriage-track unit 25 may be readily raised from the universal base or lowered to position thereupon, since the described locking train is made separable for this purpose; the self-presenting interponent 226 being mounted upon the carriage-track frame and rising 30 therewith out of the path of the carriage-dog striker 83, and dropping into place in said path when the carriage-track frame is seated upon the universal base.

Thus, without assortments of cast-iron general 35 frameworks being stored at the main factory, or losses from breakage thereof, and without the necessity of transmitting an order to the manufacturer, to take its turn in being filled, the dealer needs only to draw from his own stock a universal 40 base, and place therein the type-bar unit of a kind required by his customer, together with the ribbon-unit, and the carriage-feeding unit, and then place upon the universal base a carriage-track unit of the length required for the carriage 45 needed by the customer, thus being able to fill the order within only a few hours. He is not only enabled readily to secure the order of the customer, but is also able to collect cash payment, on the same day that the order is given, or at 50 least to have the running of the account start with that day, instead of perhaps some weeks or months later.

Upon the carriage-track unit (Figure 15) may be mounted stationary wing-scales 235 for the 55 platen 37. A support in the form of a cross-bar 236 is detachably fastened upon the opposite bars 180, 181 of the cast frame of this unit, by screws 237. The wing-scales 235 may be supported upon the cross-bar by means of the usual springs 238. 60 The scales do not need to shift up and down at the case-shift operation.

The wing-scales 235 must have the same pitch as the margin-gage racks 200, 201 and the carriage-feeding rack 160, and therefore these elements 65 need not be assembled upon the carriage-track frame to be carried in stock therewith, but a selection may be made from an assortment of different pitches of gages, scales and racks, to be mounted upon a carriage-track-frame unit of 70 appropriate length for the needs of a customer. The selected pitch of these elements would correspond with the size of the type in the selected type-action unit. Thus, a large variety of machines can be selectively made up from a relatively small stock of parts.

The Underwood back-spacing mechanism is disclosed in the patent to Helmond No. 1,414,738, of May 2, 1922, and is there shown mounted in the base-portion of the usual cast-iron framing; but in the present instance, Figures 1, 2, and 18, it is mounted to form part of the detachable carriage-escapement unit. Said back-spacing device includes a bracket consisting of a cross-bar 239 and arms 240 extending rearwardly and having a rock-shaft 241 mounted therein. Said bracket is detachably retained by screws 242 upon cross-bar 243 which forms the lower part of the bracket or casting of the carriage-escapement unit.

At the left-hand end of said rock-shaft 241 is a screw 244, which fastens the hub of a forwardly-extending lever 245, bearing a back-space key 246. The key is in line with the rear bank of type-keys at Figure 1.

The other end of said rock-shaft 241 is bent 20 to form an arm 247, from which extends upwardly a link 248, which at its upper end is detachably pivoted by a screw 249 to a moving member 250 of the back-spacing mechanism, set forth in said Helmond Patent 1,414,738. Said mechanism is illustrated at Figure 18 and needs no further description. It co-operates with the usual carriage-escapement rack 160.

It will be understood that there are several trains each of which is divided into separable parts, which separate when the carriage-track frame is lifted from the universal base. Mention has already been made of the divisibility of the line-locking train, and of the separation of the rack 160 of the escapement-train from the pinion 159; and it will also be understood that said rack 160 separates (see Figure 18) from the back-spacing mechanism, or may lift up clear thereof, whereby either assembling or disassembling of the carriage-track frame is facilitated.

The carriage-escapement and back-spacing device may be regarded as a single unit, which may be assembled and secured by the screws 167 upon the pedestal 168, before the type-action unit is inserted in place in the universal base.

The back-space key-lever 245, 246 will not obstruct either the withdrawal or assemblage of the type-action unit.

The back-spacing mechanism may be regarded as a sub-unit, which may be fastened upon the carriage-escapement unit for shipment, or it may be shipped separately therefrom and attached thereto by the dealer. It is also apparent that the back-spacing sub-unit may itself be knocked down by detaching the screws 249 and 242 before shipment.

The tabulator-unit (Figures 1, 2, and 16) is upon the outside, and attached to the rear wall 146 of the universal base. This unit includes decimal-tabulator keys 251, having stems 252 for depressing the forward arms 253 of levers that are mounted upon a fixed transverse rod 254, and have lift arms 255 extending rearwardly to a set of vertical decimal-stop blades 256. The decimal-stop blades and levers are shown mounted upon a vertical bracket 257 struck up from sheet-metal and held by screws 258 upon the rear face of the wall 146. Decimal-stop fittings of different pitches may be employed upon different typewriters, without the necessity of carrying in stock a universal base for every pitch.

The sides 259 of the bracket are bent forwardly from the rear wall 257 thereof, and the opposite attaching ears 260 are bent outwardly from the sides 259. A guide 261 is provided for the lower ends of the sliding stop-blades 256, and the usual

stop-blade guide 262 surmounts the bracket. The levers 253, 255 are not attached to the blades 256, and are readily removable from the unit after unscrewing the fulcrum-rod 254 from the arm 263 of the bracket. The unit may be packed and shipped in knocked-down condition, since the detachable key-stems 252 have at their lower ends vertical slots 264 to fit upon shouldered operating pins 265 provided upon the levers 10 253, 255.

The various units are not only interchangeable, but it is contrived for one or more members of every unit to be self-presenting to the co-operating member of the adjacent unit, when the units 15 are properly assembled together.

When attaching or detaching the tabulating unit, the carriage-track-frame unit must be off from the universal base. The tabulator-key stems 252 are guided in a two-part transverse 20 slotted bar, detachably held by screws 266 upon ears 267 that are punched in from the side walls 141, 142 of the universal base, Figure 11. The lower member 268 of the cross-bar is a support, while the upper member 269 is slotted to form a 25 guide-comb for the stems 252, and is held on the cross-bar 268 by means of screws 270.

The stops 271 upon the tabulator-key stems come to rest against plate 269, under the operation of individual return springs 272.

30 The stems 252 may be individually detached from the unit, and the levers 253, 255 may also be detached, for compactness of packing and shipment; but the unit may be readily assembled after the type-action unit has been fastened into the 35 universal base; and the ribbon-unit may be put in place either before or after the keys 252 are passed down between the type-key levers 22 and seated upon their operating pins 265. The row of keys 251 is just in rear of the typewriter-key-40 board, and forward of the transverse bar 118 of the carriage-track unit; while the tabulator-levers 253, 255 are strung beneath the universal base.

The tabulator-blades 256 operate a short universal bar 273, which forms part of a train for releasing the carriage 161 for tabulating operation. The train includes rock-shaft 274, journaled in the side walls 259 of the bracket and having an arm 275 which operates a thrust-link 50 276, the latter bearing against ear 173^a upon the lower end of the arm 173, which lifts the feed-rack 160 from the escapement-wheel pinion 159.

It will be observed that separability is provided 55 between the link 276 and the arm 173, thus favoring ready attachment of the tabulating unit and assuring that when the latter is attached and fastened in place, the link will properly present itself to the arm 173 without necessity of 60 fitting parts.

The link may be provided with a longitudinal slot 277, whereby it is guided upon a fixed pin 278 fastened upon the tabulator bracket. Upon the carriage is usually mounted a rack 279, upon 65 which are mounted adjustable column stops 280, arranged in the path of the decimal stops when the latter are elevated.

It has heretofore been found difficult to thread 70 an ink ribbon into the machine, in the cramped space in front of the platen. It is contrived by the present invention to provide more room for the operator's fingers at the ribbon spools and ribbon guides. Accordingly, the ribbon spools 114 with their circular boxes 281 and shafts 113 are 75 set back about one-half an inch from positions

heretofore occupied in Underwood machines. This brings the spools to a position rearward of the front bar 282 of the carriage, and leaves ample opportunity for the fingers to move in front of the platen for manipulating the spool and ribbon. 5

The relative position of the platen to the type-bars is unchanged. The position of the platen has been rearranged by swinging it to the rear around the pivotal point 30 of the lowermost type-bar. The type-bars together with the segment have been likewise rearranged, as if made in one piece with the platen, and swing about the same point 30. The segment therefore is rearranged in a rearwardly-inclined position, and the types therefore strike the platen on a level which is a little above the platen axis; this making an improvement by rendering the printing line more elevated and therefore more visible. 10 15

For adjusting either end of the platen minutely, either forwardly or backwardly, there is provided upon the carriage-frame a lever 284, to which the platen-axle 197 is pivoted. Said lever is fulcrumed at 285 upon the carriage 161, and is controllable by means of a slide 286, which may be adjusted forward or backward by moving 25 it up or down. The slide has a slot 287 that is inclined a little from the vertical, so that up-and-down adjustments of the slide will cause minute vibrations of the lever and platen.

The adjustment is secured by fastening a 30 screw 288, which also co-operates with a fixed pin 289 to guide the slide up and down. A similar equipment may be provided at each end of the carriage, so that either end of the platen may be 35 swung forwardly or backwardly a trifle, to secure evenness of type-impressions throughout the line of typing.

The machine may be finished by enclosing it in a mask made of thin sheet-metal. All said units may be encased by the opposite side walls 290 of the struck-up mask, Figure 13; the vertical side walls of said mask continuing forward at 291, and being bent into a bow at the front to form a masking portion 292 for the front of the typewriter-frame. Said side walls 291 and said forward portion 292 are preferably formed in one 45 piece with the opposite walls 290.

The walls of the bowed portion of the mask may be formed with inwardly-turned flanges 293. The tops of the side walls 290 of the mask are 50 level with the tops of the side bars 180, 181 of the carriage-track frame, said side bars therefore serving as finishing flanges to the tops of said side walls. The carriage-track frame may be lifted off without first removing the mask. 55

Each side and front of the mask have bent-in bottom ears 294, which are fastened by screws 294^a to the bottom 140 of the universal base.

The mask fits around all except the projecting portions of the carriage-track frame, which rises from the mask to carry the front carriage-track. That is, front and rear shoulders 182, 184 rise above the top level of the mask to receive the front and rear carriage-tracks. 60

It will be seen that the mask, with its smooth, 65 unbroken main surfaces, affords an ornamental covering for the main casting below the overhanging carriage-track frame. The trunks 212 (Figure 14) are made with extra thickness, and the mask is fitted thereto. The mask being itself 70 universal for all machines, is formed with an extra deep cutaway 294^b at these trunks. The shoulders 188 of the carriage-track frame (Figure 9) are made of extra width, so as to fill these 75 cutaways 294^b.

The side plates 290 of the mask are connected by a detachable front vertical masking plate 295, having a curved cutout upper edge at 296, corresponding to the curvature of the row of types. 5 This front plate is arched at its side portions at 297, to clear the swinging type-bars.

The top of the front plate at each side is bent back forming a tablet 298 overlying portions of the carriage-track frame.

10 The one-piece rear wall 300 of the mask is fastened by screws 301 to the base unit; said screws also fastening the stiffening flanges 302 which are bent in from the rear ends of the side walls of the mask. Said flanges 302 are flush 15 with the rear wall 300, the side edge portions of the latter being depressed at 303 to form a niche for receiving said flanges. The middle of the rear wall is bowed back at 304 to form a housing or shell concealing the tabulator unit. At the 20 tops of the front and rear portions the side walls are cut away to form contours to fit the bases of the horns or trunks of the carriage-track frame, which bases are alike for all sizes of frames.

25 At Figure 2, there is depicted a ribbon-shaft winding and shifting button 299 projecting from the main shaft through the side plate of the mask.

Variations may be resorted to within the scope 30 of the invention, and portions of the improvements may be used without others.

Having thus described my invention, I claim:

1. A knock-down typewriting machine having a framework including four parts fastened rigidly together but readily separable one from another and all fitted for interchangeability, namely, a base unit, a skeleton frame mounted thereon to support the type-actions, an overhanging carriage-track frame, said three elements each re-enforcing the other two to form a rigid framework, and a mask below the carriage-track frame and encasing the base and the type-action mount.

2. A new article of manufacture constituting a base unit fitted for universal interchangeability in a typewriting machine, and formed of one piece of sheet-metal forming a floor with struck-up high side walls provided with bent-over flanges forming seats for a carriage-track unit, 45 and formed at its sides with cut-out projecting ears for having rubber feet attached thereto, and having a rear wall bent up from said floor, and a mount for a carriage-feeding unit, said mount fixed to said floor and to said rear wall; the 50 rear ends of said side walls being bent inwardly to form flanges fastened to said rear wall.

3. A knock-down typewriting machine having a rigid framework composed mainly of a sheet-metal main base portion and a rigid carriage-track portion including a cast main frame superposed upon and rigidly attached to said base portion to form a rigid boxwork therewith, and a type-action unit having an interchangeable skeleton frame rigidly secured upon the floor of the 60 base portion and confined between the sides thereof and having opposite uprights carrying a shifting frame with a type-bar system, and having supports for a detachable ribbon-spool-winding unit, and having side sills detachably secured 65 upon the floor of said base unit, said uprights connected by a rear wall having fulcrums for the type-key levers, said base having a floor and struck-up high sides and high rear wall, said side walls extending to the front of the typewriter-keyboard, and a front wall enclosing the key- 70

board and bent up from the floor of the base, and a struck-up thin sheet-metal mask enclosing said base portion and said type-action unit and underlying said carriage-track frame, portions of said carriage-track frame extending down within said mask for attaching the carriage-track frame rigidly to the base, said mask having bent-in bottom ears that are detachably fastened up against the bottom of the floor of the universal base. 5

4. A carriage-track unit having a rectangular cast frame with front spreading trunks having horn-like tips upon which is secured a front carriage-track, and also having rear spreading trunks upon which are fastened outer cleats supporting a rear carriage-track, and two cleats secured upon the rear bar between said outer cleats, all cleats being interchangeable. 10

5. A new article of manufacture in the form of a type-action unit including a skeleton frame having a rear wall and uprights at the ends thereof and formed by portions bent forwardly from said rear wall, said frame also having side sills integral with and extending forwardly from said uprights for attachment to a base upon which said sills rest, a shifting type-bar and sub-lever system mounted upon said uprights, and members bent up from said sills and having means for arresting the up and down shifting movements of the type-bar system. 20

6. A knock-down typewriting machine having a framework including four parts fastened rigidly together but readily separable one from another and all fitted for interchangeability, namely, a base unit, a skeleton frame mounted thereon to support the type-actions, an overhanging carriage-track frame, said three elements each re-enforcing the other two to form a rigid framework, a mask below the carriage-track frame and encasing the base and the type-action unit, and a system of type-bar actions, including controlling keys, mounted upon said skeleton frame to form therewith an interchangeable unit, means being also included in said type-action unit for shifting the type-bars up and down, said base and said mask being each universal and interchangeable for all varieties of the specified type-bar units. 30

7. A new article of manufacture in the form of a type-action unit, fitted for interchangeability, said unit including a skeleton frame for fastening to a re-enforcing base, having opposite sides, a rear wall, and side sills all struck up from sheet-metal, a transverse key-lever fulcrum-bar secured to said rear wall, key levers extending forwardly from said fulcrum-bar, a transverse front guide-comb for said key-levers, a system of rearwardly striking type-bars, an upstanding segment whereon said type-bars are radially mounted, a transverse shift-frame whereon said segment is secured, rock-arms mounted upon said rear wall for guiding up and down said shift-frame, said segment and said type-bars, sub-levers to which said key-levers are individually linked, connections between said sub-levers and type-bars, said sub-levers mounted upon said shiftable frame to shift together with said type-bars, and means upon said unit for limiting the shifting of said shift-frame and type-bars; said key-levers formed with arms pendent from their fulcrums, and extending forwardly from the lower portions of said arms, and the links extending forwardly from the lower portions of said arms to said sub-levers. 40

8. A new article of manufacture in the form 45

of a type-action unit, fitted for interchangeability, said unit including a skeleton frame for fastening to a re-enforcing base, having opposite sides, a rear wall, and side sills all struck up from sheet-metal, a transverse key-lever fulcrum-bar secured to said rear wall, key-levers extending forwardly from said fulcrum-bar, a transverse front guide-comb for said key-levers, a system of rearwardly striking type-bars, an upstanding segment whereon said type-bars are radially mounted, a transverse shift-frame whereon said segment is secured, rock-arms mounted upon said rear wall for guiding up and down said shift-frame, said segment and said type-bars, sub-levers to which said key-levers are individually linked, connections between said sub-levers and type-bars, said sub-levers mounted upon said shiftable frame to shift together with said type-bars, and means upon said unit for limiting the shifting of said shift-frame and type-bars; said key-levers formed with arms pendent from their fulcrums, and extending forwardly from the lower portions of said arms, and the links extending forwardly from the lower portions of said arms to said sub-levers, said key-levers formed with portions extending upwardly and forwardly in front of said sub-levers and having bendable arms to operate a universal bar; and said unit having a dog-striker mounted thereon and operatively connected to said universal bar to actuate a carriage-feed dog-rocker but separable therefrom, said unit having a cross-bar upon which are adjustably anchored compression returning springs bearing against the pendent rear portions of the key-levers.

9. A new article of manufacture in the form of a type-action unit, fitted for interchangeability, said unit including a skeleton frame for fastening to a re-enforcing base, having opposite sides, a rear wall, and side sills all struck up from sheet-metal, a transverse key-lever fulcrum-bar secured to said rear wall, key-levers extending forwardly from said fulcrum-bar, a transverse front guide-comb for said key-levers, a system of rearwardly striking type-bars, an upstanding segment whereon said type-bars are radially mounted, a transverse shift-frame whereon said segment is secured, rock-arms mounted upon said rear wall for guiding up and down said shift-frame, said segment and said type-bars, sub-levers to which said key-levers are individually linked, connections between said sub-levers and type-bars, said sub-levers mounted upon said shiftable frame to shift together with said type-bars, and means upon said unit for limiting the shifting of said shift-frame and type-bars; said key-levers formed with arms pendent from their fulcrums, and extending forwardly from the lower portions of said arms, and the links extending forwardly from the lower portions of said arms to said sub-levers, said shift frame being of open construction to clear the type-bars, and said sub-levers being of the first order and mounted upon individual brackets attached to the front of said shifting frame, said sub-levers being upright and having various lengths, and converging from the relatively wide system of key-levers inwardly to substantial agreement with the relatively narrow system of type-bars and type-bar links.

10. A new article of manufacture in the form of a type-action unit, fitted for interchangeability, said unit including a skeleton frame for fastening to a re-enforcing base, having opposite sides, a rear wall, and side sills all struck up from

sheet-metal, a transverse key-lever fulcrum-bar secured to said rear wall, key-levers extending forwardly from said fulcrum-bar, a transverse front guide-comb for said key-levers, a system of rearwardly striking type-bars, an upstanding segment whereon said type-bars are radially mounted, a transverse shift-frame whereon said segment is secured, rock-arms mounted upon said rear wall for guiding up and down said shift-frame, said segment and said type-bars, sub-levers to which said key-levers are individually linked, connections between said sub-levers and type-bars, said sub-levers mounted upon said shiftable frame to shift together with said type-bars, means upon said unit for limiting the shifting of said shift-frame and type-bars; said key-levers formed with arms pendent from their fulcrums, and extending forwardly from the lower portions of said arms, and the links extending forwardly from the lower portions of said arms to said sub-levers, said type-bar segment being detachably mounted upon said shifting frame, and the type-bars being individually detachably mounted upon said segment; the latter being radially slotted for the type-bars and provided with a curved fulcrum-wire, and the type-bars having fulcrum-holes formed with open slots for attachment and detachment of the type-bars; the contour of the hub of each type-bar being concentric with the fulcrum-wire, and a universal segmental keeper detachably secured to the rear wall of the segment and fitted to all the type-bar hubs to retain all the type-bars; said type-bars having short operating pivot-arms extending rearwardly below the slots of the type-bars and at their rear ends detachably pivoted to the operating links, each type-bar being struck up from sheet-metal and shaped at its fulcrum-end to form three members, namely, a plate-member fitting in the radial slot of the type-bar segment for guiding the type-bar laterally, a short operating arm for pivoting to the driving link, and a hook-shape hub-member merging into said plate-member and having an open slot whereby it is detachably caught upon the fulcrum-wire, and having a segmental form constantly fitting to said universal keeper, said hook-like member protruding from said guide-plate member and extending for about ninety degrees around the fulcrum-wire.

11. A knock-down typewriting machine having a framework including four parts fastened rigidly together but readily separable one from another and all fitted for interchangeability, namely, a base unit, a skeleton frame mounted thereon to support the type-actions, an overhanging carriage-track frame, said three elements each reinforcing the other two to form a rigid framework, a mask below the carriage-track frame and encasing the base and the type-action mount, a system of type-bar actions, including controlling keys, mounted upon said skeleton frame to form therewith an interchangeable unit, means being also included in said type-action unit for shifting the type-bars up and down, said base and said mask being each universal and interchangeable for all varieties of the specified type-bar units, said type-action unit including a universal-bar mechanism, and a carriage-feeding-mechanism unit mounted detachably upon said type-action unit, for operation by said universal-bar mechanism and co-operation with the rack of a carriage supported upon said carriage-track frame, said rack being readily separable from said carriage-feeding-mechanism unit for ready

removal together with said carriage-track frame from said type-action unit.

12. A knock-down typewriting machine having a framework including four parts fastened rigidly together but readily separable one from another and all fitted for interchangeability, namely, a base unit, a skeleton frame mounted thereon to support the type-actions, an overhanging carriage-track frame, said three elements each reinforcing the other two to form a rigid framework, a mask below the carriage-track frame and encasing the base and the type-action mount, a system of type-bar actions, including controlling keys, mounted upon said skeleton frame to form an interchangeable unit, means being also included in said type-action unit for shifting the type-bars up and down, said base and said mask being each universal and interchangeable for all varieties of the specified type-bar units, said type-action unit including a universal-bar mechanism, a carriage-feeding-mechanism unit mounted detachably relatively to the type-action unit, for operation by said universal-bar mechanism and co-operation with the rack of a carriage supported upon said carriage-track frame, said rack being readily separable from said carriage-feeding-mechanism unit for ready removal together with said carriage-track frame from said type-action unit, said universal-bar mechanism including a universal bar, said key-levers having bendable arms for operating said universal bar, a striker operatively connected to said universal bar, to rock a dog-rocker of said feeding unit but leaving the feeding unit free for ready detachment, said striker in the form of a rockable member mounted upon said type-action unit and having a pin, and a ribbon-vibrator also mounted upon said type-action unit and including a laterally shiftable yoke having differentially slotted sides, said yoke being shiftable at will to engage either slotted side with the pin of said rockable member, for varying the throw of the ribbon-vibrator, the pin-engaging slots in said yoke being formed for gradual acceleration and retardation of the ribbon-vibrator movements, and a yoke-shifting train including a lever fulcrumed upon a side member of said carriage-track frame and having at its forward end a finger-piece, and a transverse detachable link extending from the rear portion of said lever inwardly to said yoke.

13. A knock-down typewriting machine having a framework including four parts fastened rigidly together but readily separable one from another and all fitted for interchangeability, namely, a base unit, a skeleton frame mounted thereon to support the type-actions, an overhanging carriage-track frame, said three elements each reinforcing the other two to form a rigid framework, a mask below the carriage-track frame and encasing the base and the type-action mount, a system of type-bar actions, including controlling keys, mounted upon said skeleton frame to form therewith an interchangeable unit, means being also included in said type-action unit for shifting the type-bars up and down, said base and said mask being each universal and interchangeable for all varieties of the specified type-bar units, said type-action unit including a universal-bar mechanism, a carriage-feeding-mechanism unit mounted detachably upon said type-action unit, for operation by said universal-bar mechanism and co-operation with the rack of a carriage supported upon said carriage-track frame, said rack being readily

separable from said carriage-feeding-mechanism unit for ready removal together with said carriage-track frame from said type-action unit, and a ribbon-winding-mechanism unit also interchangeably mounted upon said type-action unit for operation by said universal-bar mechanism; said ribbon-winding unit being a separate article of manufacture and interchangeable from said type-action unit and universal-bar mechanism, and universal for all machines, for the purposes specified, and a ribbon-vibrator mounted upon said type-action unit and operated by said universal-bar mechanism, said universal-bar mechanism operating a striker that is mounted upon said type-action unit in position to operate the dog-rocker of a carriage-feeding unit detachably mounted upon a pedestal rising from the floor of the universal base.

14. A knock-down typewriting machine having a framework including four parts fastened rigidly together but readily separable one from another and all fitted for interchangeability, namely, a base unit, a skeleton frame mounted thereon to support the type-actions, an overhanging carriage-track frame, said three elements each re-enforcing the other two to form a rigid framework, a mask below the carriage-track frame and encasing the base and the type-action mount, a system of type-bar actions, including controlling keys, mounted upon said skeleton frame to form therewith an interchangeable unit, means being also included in said type-action unit for shifting the type-bars up and down, said base and said mask being each universal and interchangeable for all varieties of the specified type-bar units, said type-action unit including a universal-bar mechanism, a carriage-feeding-mechanism unit mounted detachably upon said type-action unit, for operation by said universal-bar mechanism and co-operation with the rack of a carriage supported upon said carriage-track frame, said rack being readily separable from said carriage-feeding-mechanism unit for ready removal together with said carriage-track frame from said type-action unit, a ribbon-winding-mechanism unit also interchangeably mounted upon said type-action unit for operation by said universal-bar mechanism; said ribbon-winding unit being a separate article of manufacture and interchangeable from said type-action unit and universal-bar mechanism, and universal for all machines, for the purposes specified, a ribbon-vibrator mounted upon said type-action unit and operated by said universal-bar mechanism, said universal-bar mechanism operating a striker that is mounted upon said type-action unit in position to operate the dog-rocker of a carriage-feeding unit detachably mounted upon a pedestal rising from the floor of the universal base, said ribbon-winding unit being universally interchangeable and including a transverse sheet-metal bracket-plate extending under the type-bars from side to side of the machine and detachably mounted upon said type-action unit, and having at its ends risers and vertical spool-winding shafts mounted in brackets detachably secured to said risers, said risers extending up from the sills of said type-action unit; and a ribbon-winding train having portions divisible one from the other, one portion being mounted upon the ribbon-winding bracket, and the other portion being mounted upon the type-action unit and connected to the universal bar thereon; said winding train including a rod pivoted at one end to a rock-shaft

of the universal-bar mechanism, said rod having a pin-and-slot guide, and its upper end self-presented to the remainder of the train.

15. The combination with a platen-carriage, and forward and rear tracks therefor, said tracks forming portions of an open carriage-track frame having front and rear bars and opposite side bars, a system of type-actions including keys, beneath said carriage, a support for said type-actions, a universal-bar mechanism operated by the keys and mounted upon said support, means whereby said carriage-track frame is rigidly but removably connected to said support, said carriage-track frame having laterally projecting front horns, margin-gage devices, including a margin-gage rod, mounted between said horns for co-operation with said carriage, and an operating train extending from said margin-gage devices alongside one of said side bars of said carriage-track frame, including a bell-striker controlled by said carriage through margin-gage mechanism, said train being separably connected with said universal-bar mechanism, to enable the carriage to block the latter and lock the keys, and to be liftable away from said universal-bar mechanism as said carriage-track frame is detached from the base, and said margin-gage devices and train forming a unit which is a separate article of manufacture and shipment mountable interchangeably upon carriage-track units of various lengths.

16. The combination with a platen-carriage, and forward and rear tracks therefor, said tracks forming portions of an open carriage-track frame having front and rear bars and opposite side bars, a system of type-actions, said carriage-track frame having mounted thereon a margin-gage mechanism including a front margin-gage rod and an adjustable margin-gage thereon, and also including a train extending along one of said side bars, including a bell-striker and bell, and also including a line-locking device which is self-presented to the universal-bar train when the carriage-track frame is fastened upon the universal base; means being also provided upon said carriage-track frame for operating said margin-gage train to release the key-locking train, at will, including a release key which occupies a position at the rear of the keyboard and is mounted upon the carriage-track frame, said line-locking train including an interponent moved by the carriage into the path of a stop provided upon a feed-dog striker mounted upon the type-action unit and operable by the type-keys, said margin-release key having means whereby a lug is pulled out of the path of ear 232, so that arm 217 can no longer control rod 224, whereby the interponent 226 may be dropped to idle position.

17. A knock-down typewriting machine having a framework including four parts fastened rigidly together but readily separable one from another and all fitted for interchangeability, namely, a base unit, a skeleton frame mounted thereon to support the type-actions, an overhanging carriage-track frame, said three elements each re-enforcing the other two to form a rigid framework, a carriage mounted upon said carriage-track frame, key-controlled escapement-mechanism for said carriage, and a tabulating unit for said carriage including a bracket mounted upon the outer side of the rear wall of said universal base and having carriage-stops thereon, and including also levers extending forwardly from said bracket, and also including tabulator-

keys having stems detachably connected to the forward ends of said levers; said levers being removably mounted upon said bracket and separably connected to said carriage-stops, said tabulator-key stems being guided in a two-part transverse slotted comb-bar detachably mounted upon ears provided upon the universal base, said stems having stops against which they are normally held by return springs, said stems being individually detachable from the unit, and the levers being also detachable, said keys being just in rear of the typewriter-keyboard, and said levers being strung beneath the floor of the universal base.

18. A knock-down typewriting machine having a framework including four parts fastened rigidly together but readily separable one from another and all fitted for interchangeability, namely, a base unit, a skeleton frame mounted thereon to support the type-actions, an overhanging carriage-track frame, said three elements each re-enforcing the other two to form a rigid framework, a carriage mounted upon said carriage-track frame, an escapement-mechanism unit mounted interchangeably upon said type-action unit, and a back-spacing unit detachably and interchangeably mounted upon said escapement-unit, said back-space unit including a rock-shaft, a bracket in which said rock-shaft is journaled, said bracket being interchangeably mounted upon said carriage-escapement unit and having a forwardly-extending key-lever at one end and a back-spacing arm at the other end, said lever being detachably mounted upon said rock-shaft for packing and shipment.

19. A knock-down typewriting machine having a rigid framework composed mainly of a sheet-metal main base portion and a rigid carriage-track portion including a cast main frame superposed upon and rigidly attached to said base portion to form a rigid boxwork therewith, and a type-action unit having an interchangeable skeleton frame rigidly secured upon the floor of the base portion and confined between the sides thereof and having opposite uprights carrying a shifting frame with a type-bar system, and having supports for a detachable ribbon-spool-winding unit, and having side sills detachably secured upon the floor of said base unit, said uprights connected by a rear wall having fulcrums for the type-key levers, said base having a floor and struck-up high sides and high rear wall, said side walls extending to the front of the typewriter-keyboard, and a front wall enclosing the keyboard and bent up from the floor of the base, and a struck-up thin sheet-metal mask enclosing said base portion and said type-action unit and underlying said carriage-track frame, portions of said carriage-track frame extending down within said mask for attaching the carriage-track frame rigidly to the base, said mask having bent-in bottom ears that are detachably fastened up against the bottom of the floor of the universal base, a platen and carriage having a front bar and running upon said carriage-track frame, the ribbon-spool being encased in boxes which are below and in rear of the front bar of said carriage, to afford space for finger manipulation, the type-bar segment inclining upwardly and rearwardly, the types striking a little above the horizontal plane of the platen-axis, as specified.

20. A carriage-track unit having a rectangular cast frame with front spreading trunks having horn-like tips upon which is secured a front carriage-track, and also having rear trunks for

the rear carriage-track, said rear trunks being made of extra thickness, and a mask enclosing the unit and having corresponding cutaways, for the purpose specified.

- 5 21. In a typewriting machine, a rigid cushion-supported framework including an inner frame for supporting a system of type-actions, said inner frame having a crossbar for fulcruming a system of key-levers, a front transverse key-lever 10 guiding comb, mounts, at opposite sides of the inner frame, for supporting an up-and-down shiftable type-bar segment, and stops for limiting the segment shifts; said framework also including an outer frame for detachably mounting 15 the inner frame, said outer frame having a support for a carriage-feeding unit, and a set of top seats; and an overhanging open carriage-track frame detachably secured upon said seats to reenforce said framework.
- 20 22. A knock-down front-strike typewriting machine compounded of preassembled units, which may be separately appropriated, and put together, interchangeably, for expediting delivery of a machine having a specified style of printing 25 and a specified length of carriage and range of travel thereof, said machine therefore comprising a universal-base unit having a floor and upstanding side and rear members; a selected type-action unit having a frame, a system of type-carriers having types of the requisite style, a corresponding system of type-keys, and operating connections between said keys and type-carriers, said type-carriers, keys and connections being assembled in said frame, together with a universal-bar mechanism and type-inking means, to form said type-action unit; said universal-base unit being arranged to detachably mount the type-action unit substantially within the space included by the floor and upstanding members 30 of said base-unit; a selected carriage-track unit for mounting a platen-carriage of requisite length, including an open cast frame having front, rear and side members, said cast frame mounting front and rear carriage-tracks of proper length for the carriage and its range of travel, said cast frame having parts related to companion parts of the standing members of said base-unit for detachable support of the carriage-track unit by the base-unit; and a selected carriage-escapement unit detachably mounted on the base-unit and operable by said universal-bar mechanism of the type-action unit, said escapement unit being co-operative with a rack of proper pitch on the carriage.
- 35 23. A knock-down typewriting machine having a rigid framework composed mainly of a sheet-metal base-portion and a rigid carriage-track unit including a cast main frame superposed upon and rigidly attached to said base-portion to form a rigid boxwork therewith, and a type-action unit having a frame mounting the mechanism of said type-action unit and rigidly and detachably secured upon the floor of the base-portion and confined between the sides thereof, said 40 base-portion having high sides bent up from said floor and also a high rear wall bent up from said floor, said high sides being rigidly joined to said rear wall to form a rigid support for the superposed carriage-track unit, said sides and floor extending to the front of the keyboard.
- 45 24. A knock-down typewriting machine having a rigid framework composed mainly of a sheet-metal base-portion and a rigid carriage-track unit including a cast main frame superposed upon and rigidly attached to said base-portion

5 tion to form a rigid boxwork therewith, a type-action unit having a frame mounting the mechanism of said type-action unit and rigidly and detachably secured upon the floor of the base-portion and confined between the sides thereof, said base-portion having high sides bent up from said floor and also a high rear wall bent up from said floor, said high sides being rigidly joined to said rear wall to form a rigid support for the superposed carriage-track unit, said sides and floor extending to the front of the keyboard, the front edge portion of the floor being bent up as a low front wall adjoining the front of the keyboard, and a struck-up sheet-metal mask enclosing said base-portion and said type-action unit, and underlying said carriage-track-frame unit, portions of said carriage-track frame extending down within said mask for attaching the carriage-track frame rigidly to the base-portion, said mask having bent-in bottom ears that are detachably fastened up against the bottom of the floor of said base-portion.

10 25. In a typewriting machine, a system of fore-and-aft extending key-levers, a system of rearwardly-striking type-bars, an upstanding segment whereon said type-bars are radially mounted, a transverse shift-frame whereon said segment is secured, means mounting said shift-frame for up-and-down case-shifting movement with said segment and type-bars, sub-levers to which the key-levers are individually linked, said sub-levers mounted upon said shiftable frame to shift together with said type-bars, said key-levers formed with arms pendent from their fulcrums and extending forwardly from the lower portions of said arms, and the links extending forwardly from lower portions of said arms to said sub-levers, the type-bars being individually and detachably mounted upon said segment, the latter being radially slotted for the type-bars and provided with a curved fulcrum-wire and the type-bars having open fulcrum-slots for attachment and detachment of the type-bars to said fulcrum-wire, the contour of the hub of each type-bar being concentric with the fulcrum-wire, and a universal keeper detachably secured to the segment and fitted to all the type-bar hubs to retain all the type-bars, said type-bars having short operating arms extending below the fulcrum-slots of the type-bars and detachably pivoted at their outer ends to links connecting the type-bars to said sub-levers.

15 26. A new article of manufacture constituting a base-unit fitted for universal interchangeability in a typewriting machine, and formed of one piece of sheet-metal forming a floor with struck-up high side walls provided with bent-over flanges forming seats for a carriage-track unit, and formed at its sides with cut-out projecting ears for having rubber feet attached thereto, and having a rear wall bent up from said floor, the rear end portion of each side wall being rigidly joined to the adjacent end portion of the rear wall, one of said end portions being bent to form a flange for attachment to the other end portion.

20 27. A carriage-track unit having a cast frame formed by front and rear bars and side bars, said cast frame having front laterally-spreading trunks having horn-like tips upon which is secured a front carriage-track, and also having rear spreading trunks, upon which are fastened outer cleats supporting a rear carriage-track, and a cleat secured upon the rear bar between said outer cleats.

25 28. A knock-down typewriting machine having a frame-work including four parts fastened rig- 75

- idly together but readily separable one from another and all fitted for interchangeability, namely, a base-unit, a skeleton frame mounted thereon to support the type-actions, an overhanging carriage-track frame, said three elements each reinforcing the other two to form a rigid framework, a mask below the carriage-track frame and encasing the base and the type-action unit, and a system of type-bar actions, including controlling keys, mounted upon said skeleton frame to form therewith an interchangeable unit, said base and said mask being each universal and interchangeable for all varieties of the specified type-bar units.
- 15 29. A new article of manufacture in the form of a type-action unit fitted for interchangeability, said unit including a frame mounting the parts of said unit and arranged for fastening said unit to a reinforcing base, said frame having opposite sides and a rear wall, all struck up from sheet-metal, said unit including fore-and-aft extending key-levers, a system of rearwardly-striking type-bars, an upstanding segment radially mounting said type-bars, a transverse shift-frame whereton 5 said segment is secured, means mounted upon said first frame for guiding said shift-frame up and down together with said segment and said type-bars, sub-levers mounted upon said shiftable frame and individually linked to said key-levers, and means upon the back of said rear wall of the first frame for fulcruming said key-levers, said key-levers having arms pendent from their fulcrums and extending forwardly from the lower portions of said arms, and the links extending forwardly from the lower portions of said key-lever arms to said sub-levers, said rear wall of the first-mentioned frame being arranged to clear said links and the forwardly-extending portions of the key-levers.
- 30 30. A type-action mechanism having a frame for mounting the parts, fore-and-aft extending key-levers, a system of rearwardly-striking type-bars, an upstanding segment whereton said type-bars are radially mounted, a transverse shift-frame whereton said segment is secured, means mounting said shift-frame in said first frame for up-and-down movement together with said segment and type-bars, sub-levers to which said key-levers are individually linked, connections between 10 said sub-levers and type-bars, said sub-levers mounted upon said shiftable frame to shift together with said type-bars, said key-levers being fulcrumed at the rear of said first frame and being formed with arms pendent from their fulcrums, 15 said key-levers extending forwardly from the lower portions of said arms, and links extending forwardly from the lower portions of said arms to said sub-levers, said sub-levers being of the first order and mounted upon individual brackets attached to said shifting frame, said sub-levers having various lengths and converging from the relatively wide system of key-levers inwardly to substantial agreement with the relatively narrow system of type-bars and type-links, said sub-lever 20 brackets being arranged so that the sub-lever fulcrums afforded thereby are, with respect to the several sub-levers of different lengths, differentially disposed in vertical direction to make the arms of said sub-levers of proper ratio.
- 25 31. A knock-down typewriting machine having a framework including four parts fastened rigidly together but readily separable one from another and all fitted for interchangeability, namely, a base-unit, a skeleton frame mounted thereon to support the type-actions, an overhanging carriage-track frame, said three elements each reinforcing the other two to form a rigid framework, a mask below the carriage-track frame and encasing the base and the type-action unit, and a system of type-bar actions, including controlling keys, mounted upon said skeleton frame to form therewith an interchangeable unit, said base and said mask being each universal and interchangeable for all varieties of the specified type-bar units, said type-action unit including a universal-bar mechanism, a carriage-feeding-mechanism unit mounted detachably relatively to said type-action unit, for operation by said universal-bar mechanism and co-operation with the rack of a carriage supported upon said carriage-track frame, said rack being readily separable from said carriage-feeding-mechanism unit for ready removal together with said carriage-track frame from said type-action unit, and a ribbon-winding-mechanism unit interchangeably mounted upon 10 said type-action unit for operation by said universal-bar mechanism; said ribbon-winding unit being a separate article of manufacture and interchangeably separable from said type-action unit and universal-bar mechanism, and universal 15 for all machines, for the purposes specified.
32. In a front-strike typewriting machine, the combination of a platen-carriage and tracks therefor, said tracks forming portions of an open carriage-track frame having front and rear bars and opposite side bars, a system of type-actions including keys, a support for said type-actions, a universal-bar mechanism operable by the keys and mounted upon said support, means whereby said carriage-track frame is rigidly but removably connected to said support, margin-gage devices including a member operable by the carriage at a line-end zone determined by said margin-gage devices, and an operating train extending from said carriage-operable member, and mounted on 20 said carriage-track frame, said train including a bell-striker and being separably connected with said universal-bar mechanism to enable the carriage to block the latter, and thereby lock the keys, and to be liftable away from said universal-bar mechanism together with said carriage-track frame as the latter is detached from said type-action support.
33. In a front-strike typewriting machine, the combination of a platen-carriage and tracks therefor, said tracks forming portions of an open carriage-track frame having front and rear bars and opposite side bars, a system of type-actions including keys, a support for said type-actions, a universal-bar mechanism operable by the keys and mounted upon said support, means whereby said carriage-track frame is rigidly but removably connected to said support, margin-gage devices including a member operable by the carriage at a line-end zone determined by said margin-gage devices, and an operating train extending from said carriage-operable member, and mounted on 25 said carriage-track frame, said train including a bell-striker and being separably connected with said universal-bar mechanism to enable the carriage to block the latter, and thereby lock the keys, and to be liftable away from said universal-bar mechanism together with said carriage-track frame as the latter is detached from said type-action support, said margin-gage devices and train forming a unit which is a separate article of manufacture and shipment mountable interchangeably upon carriage-track units of various 30 lengths.
34. In a front-strike typewriting machine, the 35

- 75

combination of a platen-carriage and tracks therefor, said tracks forming portions of an open carriage-track frame having front and rear bars and opposite side bars, a system of type-actions including keys, a support for said type-actions, a universal-bar mechanism operable by the keys and mounted upon said support, means whereby said carriage-track frame is rigidly but removably connected to said support, margin-gage devices 10 including a member operable by the carriage at a line-end zone determined by said margin-gage devices, an operating train extending from said carriage-operable member, and mounted on said carriage-track frame, said train including a bell-striker and being separably connected with said universal-bar mechanism to enable the carriage to block the latter, and thereby lock the keys, and to be liftable away from said universal-bar mechanism together with said carriage-track frame 15 as the latter is detached from said type-action support, and a margin-release key mounted upon said carriage-track frame and connected to said train, whereby operation of said key may disable the said train and thereby unlock the keys.

35. A knock-down typewriting machine having a frame-work including three parts fastened rigidly together but readily separable one from another and fitted for interchangeability, namely, a base-unit having corner risers, a skeleton frame mounted thereon to support the type-actions, including type-bars, and an overhanging carriage-track frame to crown said base-unit and fastened to said corner risers, said carriage-track frame being inclusive of an open casting 30 having front and rear transverse bars that are integrally connected by opposite side bars and having formations mounting a front carriage-track and a rear carriage-track, the top of said front bar being depressed below said risers, and 35 said type-bars overlying and clear of said depressed transverse front bar of said carriage-track frame.

36. A knock-down typewriting machine having a frame-work including four parts fastened rigidly together but readily separable one from another and all fitted for interchangeability, namely, a base-unit, a skeleton frame mounted thereon to support the type-actions, an overhanging open carriage-track frame, said three 40 elements each re-enforcing the other two to form a rigid framework; and a removable mask below the carriage-track frame and encasing the base and the type-action mount; said carriage-track frame having front and rear bars and opposite 45 side bars; and a system of type-actions including keys mounted upon said skeleton frame beneath said carriage-track frame, the latter having means whereby it is detachably fastened rigidly at its corners to risers on said base; said mask having walls encasing the type-actions and the skeleton frame, there being joints between the carriage-track frame and said risers, said joints 50

being concealed by the upper edge portions of the walls of said mask, the upper portions of said mask being in continuity to said track-frame to mask the lower portions thereof.

37. A knock-down typewriting machine having a frame-work including four parts fastened rigidly together but readily separable one from another and all fitted for interchangeability, namely, a base-unit, a skeleton frame mounted thereon to support the type-actions, an overhanging carriage-track frame, said three elements each re-enforcing the other two to form a rigid framework, and a mask below the carriage-track frame and encasing the base and the type-action mount; a system of type-bar actions, including controlling keys, being mounted upon said skeleton frame to be included therewith in the interchangeable unit, said base and said mask being each universal and interchangeable for all varieties of the type-bar units, and a ribbon-winding unit forming a complete separate article of manufacture removably attached to said type-action unit of the typewriting machine, said ribbon-winding unit including a transverse bracket having means for attaching it by its ends to supports formed upon the frame of the type-action unit substantially as set forth, a pair of uprights being formed upon the ends of said bracket, separately manufactured ribbon-shaft brackets being mounted upon said uprights, each bracket carrying a vertical ribbon-spool shaft, the ribbon-spool shafts being alternatively connectible to a driving cross-shaft having a ratchet-wheel, and a rockable device being pivoted upon one of said uprights and having a driving pawl for said ratchet-wheel, said type-action unit having an operating train extending to said rockable device for rocking the latter, but separable therefrom to admit of ready detachment of the ribbon-winding unit.

38. A knock-down typewriting machine having a frame-work including three parts fastened rigidly together but readily separable one from another and fitted for interchangeability, namely, a base-unit having corner risers, a skeleton frame 45 mounted thereon to support the type-actions, including type-bars, and an overhanging carriage-track frame to crown said base-unit and fastened to said corner risers, said carriage-track frame being inclusive of an open casting having front 50 and rear transverse bars that are integrally connected by opposite side bars and having formations mounting a front carriage-track and a rear carriage-track, the top of said front bar being depressed below said risers, and said type-bars 55 overlying and clear of said depressed transverse front bar of said carriage-track frame, said carriage-track frame unit including a bracket detachably secured upon said rear bar and having a stub-shaft carrying a carriage-driving spring-barrel.

BURNHAM C. STICKNEY.
